UNITED STATES PATENT OFFICE.

NICHOLAS S. VEDDER AND FRANCIS RITCHIE, OF TROY, AND TOBIAS S. HEISTER, OF LANSINGBURG, ASSIGNORS TO NICHOLAS S. VEDDER, OF TROY, NEW YORK.

DESIGN FOR HEATING-STOVE.

Specification forming part of Design No. 7,014, dated December 2, 1873; application filed September 12, 1873.
[Term of Patent 7 years.]

To all whom it may concern:

Be it known that we, NICHOLAS S. VEDDER and FRANCIS RITCHIE, residents of the city of Troy, in the county of Rensselaer and State of New York, and TOBIAS S. HEISTER, of Lansingburg, in said county and State, have jointly invented and produced a new and original Design for the Top and Base of Stoves, of which the following is a specification, reference being had to the accompanying wood cut or engraving of a stove, which embodies our said new design.

One part of our invention consists of the design for the cover A, as distinguished by the ornamental moldings b, c, and d, all shaped and arranged together on and around the upwardly and inwardly inclined lower portion of the oval cover, substantially as shown in the aforesaid cut. The molding b consists of the smooth, steeply-inclined lower rim, separated by a ledge from the concave upper part, which has thereon a row of raised quadrangular ornaments, all connected together at their lateral corners, and otherwise shaped and arranged, as shown in the engraving. The molding c consists of a curved inclined surface, having thereon a series of raised circular or oval ornaments, all connected in a row, and each bearing a lobed ornament arranged thereon, as shown in the cut. The ornamental molding d consists of the narrow beads next to the molding c, and the row of closely-joined, alternately tall and short, upwardly and inwardly pointing ornaments, based on the narrow beads, as shown in the cut.

The upper portion e of the cover may have any desired shape or ornamental configuration.

The general oval horizontal outline and upward and inward inclination of the cover A are not new; and a cover of such general outlines with encircling ornamental moldings thereon is not new; and our invention, in regard to the design for the cover A, is limited to the combination of the moldings b, c, and d, constituted, shaped, and arranged together and around the oval inclined cover, as above specified.

A top stove-plate having an oval inclined rim with ornamental moldings thereon is not

new; but another part of our invention consists of a design for the top-plate F, as distinguished by the ornamental moldings g, h, and i, all constituted, shaped, and arranged together upon and around the inclined oval-rim portion of the plate, substantially as hereinafter specified, and shown in the accompanying engraving. The upper and inner molding, g, consists of an inclined surface with a row of diamond-shaped ornaments, connected together by round or oval beads, as shown in the cut. The middle molding h consists of an inclined surface, having thereon a row of round or oval projections, each having a radiating lobed ornament thereon, and all shaped and connected together with a bead between each two, substantially as shown in the illustration. The outer and lower molding, i, consists of the smooth lower rim, the upper concave surface having thereon a row of separate quadrangular-pointed ornaments with lateral projections, and the intermediate transversely-grooved band with angular projections thereon, substantially as represented in the wood-cut.

Another part of our invention consists of the design for the base-plate J, as distinguished by the ornamental moldings k, l, and m, all shaped and arranged together, as hereinafter specified, and shown in the aforesaid engraving. The molding k consists of a concave surface, having thereon a row of oval projections, shaped and connected together, as shown in the engraving. The molding l consists of a lower smooth rim, the adjacent ribbed or fluted band, and the upper portion having thereon the row of separate quadrangular ornaments with lateral projections at their angles, as shown in the print. The molding m consists of the lower smooth rim, the adjacent scalloped band, the row of separate angular projections, and the round upper band having scroll-like ends bordering the hearth, all as shown in the engraving.

The general shape of the base-plate J is not new; and we do not claim the design for either the urn, the feet or legs, the front-draft register-frame, or the fire-door or its frame, shown in the accompanying illustration.

What we claim as our invention is—

1. The design for the cover A, as distinguished by the ornamental moldings b, c, and d, composed, shaped, and arranged together substantially as described and shown.

2. The design for the top-plate F, composed of the ornamental moldings g, h, and i, shaped and arranged together substantially as described and represented.

3. The design for the base-plate J, as char-

acterized by the ornamental moldings k, l, and m, all constituted, shaped, and arranged thereon, substantially as shown and described.

NICHOLAS S. VEDDER.

FRANCIS RITCHIE.

TOBIAS S. HEISTER.
